UNITED STATES PATENT OFFICE.

GEORGE A. NELSON, OF CHICAGO, ILLINOIS.

FOLDING BED.

SPECIFICATION forming part of Letters Patent No. 388,999, dated September 4, 1888.

Application filed August 17, 1886. Serial No. 211,114. (No model.)

To all whom it may concern:

Be it known that I, GEORGE A. NELSON, of Chicago, in the county of Cook and State of Illinois, have invented certain new and useful Improvements in Folding Beds, of which the following is a full, clear, and exact description, that will enable others to make and use the same, reference being had to the accompanying drawings, forming a part of this specification.

This invention relates to improvements in that class of beds which fold up less than full length; and the same consists of certain novel features in the construction, arrangement, and operation of the several parts, as will be hereinafter set forth, and pointed out in the claim.

Figure 1 is a broken-away longitudinal section looking at the opposite inner side, the bed being in a vertical or folded position; Fig. 2, a longitudinal section looking at the opposite inside, the bed proper being in a horizontal position ready for use, with parts broken away. Fig. 3 shows the foot or a part of the bed-frame broken away in Fig. 2. Figs. 4, 5, and 6 show detached details of construction; Fig. 7, a longitudinal section.

In the drawings, A represents the wardrobe back-case, and B the bed proper.

In the construction of the bed-frame the side rails, C, are made in two parts, being cut in two near the head end, as shown in Fig. 2, the two parts being adjustably secured together so as to fold one upon the other by means of the hinge or hinges a. The head ends C' of the side rails are in turn adjustably secured to the inside back part of the case A by means of the strap-hinge a', provided with a hook end adapted to engage with the eyebolt a''. By this simple arrangement the frame or bed proper may be easily detached and removed from the back-case, and when folding or unfolding the bed the head ends of the rails are adapted to assume either a vertical or a horizontal position, as may be required, the two parts folding against each other when the bed is arranged vertically, as shown in Fig. 1.

The ends of the lever or supporting-brace D are bifurcated (see Fig. 4) and turned at right angles and in opposite directions relative to each other, as shown in Fig. 2. The upper

inner end of the lever or levers D is pivoted to the lower outer corner of the head part of the side rails, and extends from this point in a diagonal direction to the floor when the bed is lowered, and assumes a horizontal position on the inside bottom of the back-case (see Fig. 1) when the bed is folded.

a³ a⁴ are two rollers journaled in the lower end of the lever D, (see Fig. 4,) which are intended to have frictional contact with the floor when the bed is turned down, as shown in Fig. 2. The lower end of the lever D' is inserted between the rollers a³ a⁴, and is mounted upon the shaft a⁵, the upper end of this lever being pivoted to the inner side and near the longitudinal center of the side rail or rails. b is a friction roller or rollers journaled in the lower front edge of the back-case to receive the frictional contact of the lever or levers D, and provides a rolling bearing for the same, so as to ease the weight of the bed and facilitate the labor in changing from one position to the other. The levers D D' and parts named in connection with the same are in duplicate, companion levers being attached to the other bed-rail, which is not shown.

By means of this construction and arrangement the bed is easily and conveniently raised or lowered or moved from one part of the room to another, and at the same time strongly supported when resting in a horizontal position. When the bed is folded, the levers assume the position shown in Fig. 1, the friction-rollers in the joining ends of said levers being raised from contact with the floor. The notched end of the horizontal rack bar or bars E, arranged on the inside of the bed-rails, is adapted to be adjusted to different positions on the pin b', formed on the lever D'. The opposite ends of the rack-bars are attached to the ends of the mattress foot-rail F, and serve to stretch and keep the mattress taut.

d is one of two brackets placed on the inside of each bed-rail close to the foot, which receives and supports the ends of the mattress-rail F.

Having thus described my invention, what I claim as new, and desire to secure by Letters Patent, is—

In a folding bed, the combination, with the

side rails constructed in two parts, as described, of the rack bar or bars E, arranged on the inner sides of and parallel with said rails, the foot-rail F, to the respective ends of which are attached the outer ends of the rack-bars E, the brackets d, secured to the inner sides of the side rails and supporting the ends of the foot-rail F, the lever or levers D', having the pin b' formed thereon, and which engages 5 with the notched end of said rack-bars, and

the companion levers D, having one end pivoted to the lower ends of the levers D' and the opposite ends attached to the head ends of the side rails, all substantially as and for the purpose described.

GEORGE A. NELSON.
